UNITED STATES PATENT OFFICE.

S. ROBERT SCHWARTZ AND AUGUST BOSTROEM, OF NEW YORK, N. Y., ASSIGNEES TO
SAID SCHWARTZ.

MOUNTING LAMP SHADE.

Application filed November 17, 1920. Serial No. 424,681.

To all whom it may concern:

Be it known that we, SAMUEL ROBERT SCHWARTZ and AUGUST BOSTROEM, citizens of the United States of America, residing at New York, in the county of New York and State of New York, have invented new and useful Improvements in Mounting Lamp Shades, of which the following is a specification.

10 Our invention relates to improvements in mounting lamp shades and particularly to simple and effective means for supporting the shades used on portable electric lamps. It is illustrated in the accompanying drawings and will be described in its application to the latter type of lamp, but it is evident that it may have other applications.

15 It is well known in electric portable lamps to mount an elongated shade on a longitudinal axis by providing a pivotal support at each end of the shade. A lamp socket for holding an incandescent lamp is mounted within the shade and coaxially with the same. The electric wires for this socket pass 20 through the pivotal support of the lamp, through the end of the shade and into the socket. It has heretofore been the custom to form a hole in the end of the shade through which the wiring may pass, but this had the 25 disadvantage that when for any reason it was desired to remove the shade it became necessary to disconnect the wiring from the socket and to remove the socket from its support before the shade could be removed.

30 35 It is one of the objects of our invention to provide a form of mounting for a pivotally supported lamp shade designed to allow the shade to be readily removed. It is especially adapted for use with glass shades, 40 which are frequently broken and therefore must be frequently replaced. Other and further objects will appear from the specification and will be pointed out in the claims.

We attain these objects by the structure 45 illustrated in the accompanying drawings, in which—

Fig. 1 illustrates the application of our invention to a portable electric lamp;

Fig. 2 shows a detail view of our invention, this view being partly in section along the line 2—2 of Fig. 3 and in the direction indicated by the arrows;

Fig. 3 is an end elevation of our invention; Fig. 4 is a sectional view on the line 2—2

of Fig. 3, showing the portion of the lamp shade opposite to that at which our invention is applied, together with the mounting of this opposite portion;

Fig. 5 is a view similar to Fig. 2, showing a modification of our invention;

Fig. 6 is a view similar to Fig. 2, showing another modification of our invention.

Fig. 1 shows a portable electric lamp of well-known type, consisting of a base E, a bracket arm C, pivotally joined to the base by the swivel-joint D and carrying at its upper end a lamp socket F which is appropriately wired up in the customary way by wires passing through the bracket arm. A shade B is pivotally mounted over the lamp socket F, as will be explained later in detail, the two pivots being axially alined and being coaxial with the lamp socket. Our invention is generally designated by A, and will now be described in detail.

To understand the purpose of our invention it will first be necessary to describe the mounting of the shade B. The latter is constructed with a slot 1 at one end extending from its lower rim to near the middle of the end. The slot is of sufficient width to permit the base of the socket F to slide into it. When in this position the shade pivots about the base of the socket, but is at the same time free to slide out of engagement with same. Our invention provides a simple locking means whereby the shade is prevented from sliding out of engagement with the socket unless the locking means is released. Said locking means consists of a small plate 4 pivotally mounted on an extension of the bracket C and carrying at its free end in threaded engagement a set-screw 5 which is free to move axially through a small hole 3 in the end of the shade.

At its opposite end the shade is also pivotally mounted as will be clear from an inspection of Fig. 4. A set screw 7 is freely mounted in the bracket C and passes through a hole 6 in the shade B. A wing-nut 9 is in threaded engagement with the screw 7 to keep it in place and a washer 8 is interposed between the shade B and the wing-nut 9, for obvious reasons.

From the above description the manner of using the device will be easily understood. To remove the shade B from its mounting it is only necessary to move screw 5 out of

engagement with the shade and to such a point that it will not interfere with removal of the shade. Next, screw 7 is moved out of engagement with the shade, after 5 moving the wing-nut 9. The shade is now held only in sliding engagement between bracket C and the walls of slot 1 and can be readily removed by simply sliding it out of engagement. To replace the shade the 10 above operations are performed in reverse order. During these operations the electric wiring is in no way disturbed.

The advantages of our device are now apparent, since the shade is removable after 15 merely adjusting two screws, and without in any way disturbing the wiring.

In Fig. 5 is shown a modified form of our invention, here designated by A'. A socket F' is as before mounted on an extension of 20 the bracket C' and within the shade B' which has a slot 1'. The latter, in this modification, is seated on an extension of the bracket C' and not on the lamp socket as in the other form of our invention. This 25 last-mentioned extension pivotally carries the plate 4' which carries at its free end the pin 5', slideable with relation to the plate, but capable of being clamped thereto by set screw 10'. The pin is in sliding engagement with shade B' by the provision 30 in the latter of a hole 3' into which the pin may move.

The modification of our invention shown in Fig. 6 is designated by A''. It differs 35 from the form of Fig. 2 in the addition of a nut 11'' to limit motion of the shade with relation to the screw. Parts 3'', 4'' and 5'' are identical with parts 3, 4 and 5 of Figure 2.

40 We claim:

1. In a lamp, a shade having at one end a 45 hole whereby this end may be pivotally mounted and at its other end a slot whereby the shade may be mounted pivotally without preventing axial movement nor movement transverse to the axis, and a hole 50 in the shade adapted to receive means which will prevent the above-mentioned transverse movement without destroying the freedom 55 of movement in other directions.

2. In a lamp, a shade, a hole in one end of 55 said shade, a slot in the other end of said shade permitting the shade to move transversely to its axis, and a hole in said other end of said shade, supporting means engaging said first-mentioned hole and said slot, and means engaging said second hole to restrict the movement of the shade.

3. In a lamp, a shade open at one side, a 60 hole in one end of said shade, an elongated slot debouching into the open side in the other end of the shade and permitting movement of the shade transversely to its axis, and a hole in said other end adjacent to said 65 slot, supporting means engaging said slot

and one of said holes, and means engaging said second hole to restrict the movement of the shade.

4. In a lamp, a shade, a bracket, means on 70 said bracket for pivotally supporting one end of said shade, means on said bracket for allowing pivotal motion of the other end of said shade and also allowing the shade to move in the direction of the axis of pivoting, and in a direction transverse thereto; and means carried by said bracket whereby the second-mentioned end of the shade may be prevented from moving in said transverse direction.

5. In a lamp, a shade, a hole in one end 80 of said shade, a slot in the other end of said shade, a bracket, means on said bracket adapted to coact with the hole in the shade, whereby a pivotal mounting is provided, and means on said bracket adapted to coact 85 with the slot in the shade whereby a pivotal and slideable mounting is provided.

6. In a lamp, a shade, a hole in one end 90 of said shade, a slot in the other end of said shade, a bracket, means on said bracket adapted to coact with the hole in the shade whereby a pivotal mounting is provided, means on said bracket adapted to coact with the slot in the shade whereby a mounting 95 is provided which will permit pivotal motion and motion in the direction of the axis of said pivotal motion and in a direction transverse to said axis, and means on said bracket adapted to engage the shade so as to prevent the said transverse motion.

7. In a lamp, a shade, a hole in one end of 100 said shade, a slot in the other end of said shade, a hole in said last-mentioned end of said shade, a bracket, means on said bracket which may coact with the first-mentioned hole whereby a pivotal mounting is provided, means on said bracket which may coact with the slot in the shade whereby a mounting is provided which will permit pivotal motion and motion in the direction of the axis of said pivotal motion and in a direction transverse to said axis, and means on said bracket adapted to engage said second-mentioned hole so as to prevent the said 105 transverse motion.

8. In a lamp, a shade pivotally mounted at one end and at its other end mounted so as to be free to move pivotally in the direction of the axis of pivoting or in a direction transverse thereto, a pivotally mounted plate, means carried by said plate adapted to coact with said shade, whereby the mounting of the last mentioned end is changed to one permitting pivotal motion and axial motion but not transverse motion.

9. In a lamp, a shade pivotally mounted at one end, and at its other end mounted so as to be free to move pivotally in the direction of the axis of pivoting or in a direction transverse thereto, a bracket, means 110

- pivotsly mounted on said bracket, and means on the shade adapted to coact with said pivotally mounted means whereby the mounting of the last mentioned end is 5 changed to one permitting pivotal motion and axial motion but not transverse motion.
10. In a lamp, a shade, a bracket, a hole in one end of said shade, means carried by said bracket adapted to coact with said hole to provide a pivotal support for the shade, a slot in the other end of said shade, a second means on said bracket adapted to slide into said slot and to form a pivotal support for the shade when engaging the bottom of the 15 slot, and means in pivotal relation with said second means whereby said second means is held in engagement with the bottom of the slot.
11. In a lamp, a shade, a bracket, a hole in one end of said shade, means carried by said bracket adapted to coact with said hole to provide a pivotal support for the shade, a slot in the other end of said shade, a second means on said bracket adapted to 20 slide into said slot, means in pivotal relation with said second means, and means on the shade adapted to coact with said last-mentioned means, whereby the second means is held in engagement with the bottom of the slot.
12. In a lamp, a shade, a bracket, a hole in one end of said shade, means carried by said bracket adapted to coact with said hole to provide a pivotal support for the shade, a slot in the other end of said shade, a hole in the last-named end of said shade, a second means on said bracket adapted to 25 slide into said slot, means in pivotal relation with said second means and means carried by said last-named means adapted to slidably engage the second mentioned hole in the shade whereby said means is held in engagement with the bottom of the slot.
13. In a lamp, a shade, a bracket, a hole in one end of said shade, means carried by said bracket adapted to coact with said hole to provide a pivotal support for the shade, a slot in the other end of said shade, a hole 30 in the last-mentioned end of said shade, an extension on the bracket, a lamp socket carried by said extension, said lamp socket and slot adapted to have sliding engagement with each other and pivotal engagement when the lamp socket contacts with the bottom of the slot, electric wiring passing through the bracket, through the extension and into the socket, a plate pivotally mounted on the extension, an adjusting screw mounted in threaded engagement with the plate and adapted when adjusted to slidably engage the second mentioned hole for the purpose of keeping the lamp socket in engagement with the bottom of the slot, all for the purpose of enabling the shade to be 35 readily removed and replaced without interfering with the electric wiring.
14. In a lamp, a shade, a bracket, a hole in one end of said shade, means carried by said bracket adapted to coact with said hole to provide a pivotal support for the shade, a slot in the other end of said shade, a hole in the last-mentioned end of said shade, an extension on the bracket, a lamp socket carried by said extension, said lamp 40 socket and slot adapted to have sliding engagement with each other and pivotal engagement when the lamp socket contacts with the bottom of the slot, electric wiring passing through the bracket, through the extension and into the socket, a plate pivotally mounted on the extension, an adjusting screw mounted in threaded engagement with the plate and adapted when adjusted to slidably engage the second mentioned hole for the purpose of keeping the lamp socket in engagement with the bottom of the slot, and a nut mounted on the end of the adjusting screw so as to prevent disengagement of the said screw and the second-mentioned hole, all for the purpose of enabling the shade to be readily removed and replaced without interfering with the electric wiring.
- In testimony whereof, we have signed our names to this specification in the presence of two subscribing witnesses, this 18th day of November, 1920.
